Primary Examiner—Cathron C Brooks*Assistant Examiner*—Kevin K Rudzinski(74) *Attorney, Agent, or Firm*—Rabin & Berdo, PC(57) **CLAIM**

The ornamental design for a lighting equipment, as shown and described.

DESCRIPTION

FIG. 1 is a perspective view of a lighting equipment showing our new design;

FIG. 2 is a front elevation view thereof, the rear elevation view being identical;

FIG. 3 is a right side view thereof, the left side view being identical;

FIG. 4 is a top plan view thereof; the bottom plan view being identical;

FIG. 5 is a sectional view thereof taken on line 5—5 of FIG. 2 showing no illustration of inside mechanism; and,

FIG. 6 is a referential view showing a usage state, a stand the present article is fitted therein is shown in broken lines forming no part of the claimed design.

The broken line showing is for illustrative purposes only and forms no part of the claimed design.
